(57) **CLAIM**

The ornamental design for a leg mount, as shown and described.

DESCRIPTION

FIG. 1 is a top perspective view of a leg mount, showing my design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 a bottom view thereof; and,

FIG. 8 is a bottom perspective view thereof.

The broken lines are shown for the purpose of illustrating portions of the article that form no part of the claimed design.
